UNITED STATES PATENT OFFICE.

JOSEPH MARTIN, OF MUNICH, GERMANY.

FEED-WATER HEATER.

Application filed August 29, 1921. Serial No. 496,736.

(GRANTED UNDER THE PROVISIONS OF THE ACT OF MARCH 3, 1921, 41 STAT. L., 1313.)

To all whom it may concern:

Be it known that I, JOSEPH MARTIN, a citizen of the German Republic, residing at 40 Bauerstrasse, Munich, Bavaria, Germany, have invented certain new and useful Improvements in Feed-Water Heaters (for which I have filed applications in Germany Mar. 6, 1919, Patent No. 341,791; Germany July 21, 1919, Patent No. 350,878; 10 Italy June 30, 1920; Great Britain July 2, 1920, Patent No. 161,879; Belgium July 5, 1920, Patent No. 288,670; France July 9, 1920, Patent No. 520,126; Switzerland July 12, 1920, Patent No. 91,968; Netherlands 15 July 21, 1920, Patent No. 8,003; Czechoslovakia Nov. 24, 1920), of which the following is a specification.

My invention relates to feed-water heaters, and, in particular, to such feed-water heaters in which the feed-water tubes are disposed vertically and are rolled into an elevated water-chamber, which is subdivided into a plurality of cells for grouping the tubes and thereby regulating the circulation 25 of the water.

It is an essential feature of my invention to provide means for eliminating and removing as far as possible the gases, such as air, carbon dioxide and the like, contained 30 in the water, which gases would cause a rusting of the iron parts, in particular, of the parts made of wrought iron, so that the whole feed-water heater may be made cheaply, of wrought iron.

A further object of my invention is to provide for the purpose of subdividing the water-chambers for grouping the water tubes, a special cell frame, which may be inserted into the water chamber and again 40 be removed therefrom.

A further object of the present invention is to provide means, for allowing of easily shifting the cell frame on its support without it being necessary to caulk the water tubes which are rolled into the bottom of the chamber, and to level said tubes with said bottom.

A further object of the invention is to form the cell frame in the water chamber in such a manner, that a continuous gap is left between said frame and the roof of the water chamber, through which gap the eliminated gases may pass off.

A further object of the present invention is to provide in those water tubes in which 55 in consequence of the heating, a lively liberation of gases already takes place, means which will have a centrifuging effect on the water flowing through the tubes, and thereby effect an increased degasification. 60

A further object of the invention is to allow of constructing the whole feed-water heater of wrought iron.

These and other objects and advantages 65 of the present invention and its design will be fully disclosed in and by the following specification, reference being had to the accompanying drawing, in which

Fig. 1 is a part of a feed-water heater, 70 shown partly in section;

Fig. 2 is a transverse section through the feed-water heater according to Fig. 1.

Fig. 3 is a plan view of the feed-water 75 heater.

Fig. 4 shows, on a larger scale, a longitudinal section through a part of the water chamber, the tube ends, the cell frame and the supporting plate for the latter.

In a feed-water heater of the kind as 80 shown in the drawing water-chambers are formed by the two flattened tubes *a* and *b*, into the bottoms of which U-shaped preheating tubes *c* and *d* are rolled, which alternately connect the chambers *a* and *b*. Cell-shaped frames, having no bottoms and covers and being composed of plates *e* and *f*, riveted together, are fitted into the chambers *a* and *b*, subdividing these into cells, so 85 that always one cell of the chamber *a* is in communication with a cell of chamber *b*, the communication being made by a preheating tube. The walls of the frame cells are partly perforated, to ensure that the water flows in a predetermined direction, for instance, through all preheating tubes, one after the other. These cell frames are not of the full height of the water chambers, so that a continuous gap *g* remains between 90 their upper edge and the roof of the water chambers through which gap all cells communicate within one chamber. These cell frames are separate units and can be inserted into and removed from the water chambers if the latter are provided with a 100 suitable door. The water chambers could also

105

be welded close, after the cell-frames have been fitted into them, but it is of advantage to provide a sealable door, for inserting and removing the cell-frames in order to obtain sufficient clear space in the water chambers in case of repairs and for cleaning the heater. With the said cell-frames also the inner closures *h* which are provided in the covers of the water chambers opposite to the openings of the preheating tubes *c* and *d*, may be inserted and removed and placed aside. For facilitating the moving of the said cell-frames within the water chambers, I provide between the bottom of the water chamber and the cell-frame a plate *i*, (Fig. 4), which is perforated so that the ends of the preheating tubes fit into these holes. This affords a smooth surface on which the cell frames rest and may slide, without it being necessary to caulk and level the expanded ends of the feed-water tubes.

In order to prevent the rusting of the wrought iron parts, by the use of which alone it is possible to construct the feed water heater both cheaply and compactly, I provide means, which secure as perfectly as possible a removal of the gases contained in the feed water, such as air, carbon dioxide and the like, which gases would particularly favor such rusting. These means consist of strips of sheet metal, which are helically twisted and which after being inserted into the preheating tubes, cause a whirling of the water flowing rapidly through the tubes. These whirls have the effect that the gas particles are driven away from the walls of the tubes towards the center, where they rise along the said twisted sheet metal strips. I may employ such twisted strips in all feed water tubes, but this would produce a rather great resistance for the water, so that the pressure of the feed water would have to be very high. I therefore provide such twisted strips only in those tubes, which, in consequence of their high temperature, already have a considerable elimination of gases. In the feed water heater shown, such twisted strips are fitted into the tubes *k*, *l* and *m*, in the assumption that these tubes show the greatest elimination of gas owing to their raised temperature. These twisted strips *n* are provided with narrow, rectangular slots *o* extending longitudinally, which slots serve to collect the gas bubbles when the water is still, and to offer them a possibility of adhesion, so that the walls of the tubes remain as free as possible of gas bubbles, even when the water is quiet and not moving. By such an arrangement of the twisted strips it is attained that, without any uneconomic raising of the water pressure, the elimination of gas is so complete, that rusting will not take place even in those tubes in which the strips are not arranged. The gases eliminated rise in the tubes *k*, *l*, *m*, etc., collect

above the cell frames in the chambers *a* and *b* in the continuous small air passage *g*, whence they are allowed to pass off.

The water chamber may also be composed of more than two flattened tubes, as shown, each tube containing its cell frame, and the individual cells of the several chamber tubes being alternately connected by the preheating tubes:

By this arrangement I obtain a feed water heater which is light and may be cheaply constructed of wrought iron, and which is, in all parts, readily and quickly accessible for the purpose of cleaning and making repairs, and in which the danger of rusting is reduced to a minimum.

Having thus described my invention what I claim as new and desire to secure by Letters Patent is:

1. In a feed-water heater an elevated water chamber, a removable cell frame in said water chamber, a small air passage connecting all cells being provided between the cell frame and the roof of the chamber, and the cells being connected in pairs by preheating tubes.

2. In a feed-water heater an elevated water chamber, a removable cell frame in said water chamber, a perforated plate between the cell frame and the bottom of the chamber, the cells being connected in pairs by preheating tubes, and the ends of said preheating tubes entering the holes in said perforated plate.

3. In a feed-water heater an elevated water chamber, a cell frame in said water chamber, a continuous small air passage between the cell frame and the cover of the chamber, the cells being connected in pairs by preheating tubes, and twisted strips of sheet metal being arranged in the preheating tubes.

4. In a feed-water heater an elevated water chamber, a cell frame in said water chamber, a continuous small air passage between the cell frame and the cover of the chamber, the cells being connected in pairs by preheating tubes, twisted strips of sheet metal in said preheating tubes, and longitudinal, rectangular slots in the said sheet metal strips.

5. In a feed-water heater an elevated water chamber, a cell frame in said water chamber, a continuous small air passage between the cell frame and the cover of the chamber, the cells being connected in pairs by preheating tubes, twisted strips of sheet metal in those preheating tubes, in which, in consequence of their high temperature a high elimination of gases appears, and longitudinal, rectangular slots in said sheet metal strips.

6. In a feed-water heater a plurality of wrought iron flattened tubes, a removable cell frame in each tube, a continuous small air passage between the cell frame and roof

of the tube, a perforated plate between cell frame and bottom of the flattened tube, each cell in the one flattened tube communicating through a preheating tube with a cell in another flattened tube, the ends of said preheating tubes entering into the holes in said perforated plate, twisted strips of sheet

metal in those preheating tubes in which, owing to their high temperature a high elimination of gas occurs, and longitudinal, rectangular slots in said sheet metal strips. 10

In testimony whereof I affix my signature.

JOSEPH MARTIN.
